Des. 186,533
Patented Nov. 3, 1959

186,533

WALL CLOCK

Nils Magnus, Tornquist, Honey Brook, Pa., assignor to
The Sessions Clock Co., Forestville, Conn., a corpora-
tion of Connecticut

Application March 3, 1959, Serial No. 54,817

Term of patent 14 years

(Cl. D42—7)

Fig. 1 is a front elevational view of a wall clock, showing my new design, and

Fig. 2 is a side elevational view of the clock shown in Fig. 1.

I claim:

The ornamental design for a wall clock, substantially as shown.
